UNITED STATES PATENT OFFICE

WILLIAM K. PORTER, OF PITTSBURGH, PENNSYLVANIA.

SIGNAL APPARATUS.

1,162,646.

Specification of Letters Patent. Patented Nov. 30, 1915

Application filed June 3, 1915. Serial No. 31,992.

To all whom it may concern:

Be it known that I, WILLIAM K. PORTER, a citizen of the United States, residing at Pittsburgh, in the county of Allegheny and State of Pennsylvania, have invented certain new and useful Improvements in Signal Apparatus, of which the following is a specification.

The object of the present invention is to provide a signal device especially adapted for vehicles, the novel characteristics of which are the use of illuminating signals of predetermined colors, under the control of the operator of the vehicle, for indicating the direction of contemplated movement to the approaching traffic or pedestrians and the provision of means for maintenance of illumination for the signal during night while enabling discontinuance thereof in the day, excepting when needed for the purpose of signaling.

The invention consists essentially of a casing containing a light, revoluble lenses of different colors associated therewith, and means for rotating the lenses, together with suitable sources of electric current for the light, and means for rendering the current available upon operation of the rotating means, or continuous without regard to said operating instrumentalities.

It is further contemplated to use retarding means for the operating member of this device so as to prevent improper functioning of the signals as well as insure practically automatic adjustment of the signal lenses in their relative positions.

For a full understanding of the present invention, reference is to be had to the following description and the accompanying drawings, in which:

Figure 1 is a fragmentary side elevation of a vehicle, showing the application of my light and signal in the preferred location. Fig. 2 is a vertical sectional view through Fig. 2 is a vertical sectional view through the light construction of my signal device. Fig. 3 is a horizontal sectional view through the embodiment of my invention. Fig. 4 is a rear elevation, parts being broken away and shown in section to more clearly disclose the details of construction. Fig. 5 is a diagrammatic view showing more clearly the circuit controlling instrumentalities for the signal lights. Fig. 6 is a vertical sectional view taken about on the line 6—6 of Fig. 4. Fig. 7 is a vertical sectional view on the line 7—7 of Fig. 2, showing more clearly

a light reflector. Fig. 8 is a detail view of the retarding means for the operating member of this device.

Throughout the following detail description, and on the several figures of the drawings, similar parts are referred to by like reference characters.

Referring to the drawings, and specifically describing my device, the numeral 1 designates a motor vehicle preferably, to the dashboard 2 of which is connected at each side a lamp casing 3. It will be understood that while I describe the signal devices as particularly utilized in side lights, it is equally operable and adapted for headlight arrangements as may be preferred. Both of the side lights are of exactly the same construction and only one, therefore, will be described.

4 designates a projection of the casing of a lamp which projects forwardly from a spherical body 5 within which is located an electric bulb or light 6. Each lamp is supported upon the upturned extremity of a tubular support 7 which is suitably secured by brackets 8, in rear of the dashboard of the vehicle. Within the body 5 is located a lens carrying member 9 supported preferably upon a horizontal gear member 10. The member 9 supports a plurality of lenses of different color designated, for the purposes of this description, a green lens 11 at one side, a white lens 12 in front, and a red lens 13 at the opposite side. I desire it to be particularly understood that the reference to these particular colored lenses is for illustrative purposes only because it is within the purview of the invention to utilize any desired colors for carrying out the functions of this signaling apparatus.

The use of colored signals is at the present time the best known expedient for handling traffic and the arrangement of the colored lenses hereinbefore mentioned is the carrying out of a desired arrangement of signals that would best serve the purpose of indicating to the traffic officer or other pedestrians and vehicles, the direction in which the vehicle is to be operated at intersecting points. With this in view, it will be noted that the white lens is positioned so as to disclose a forward white light under normal conditions of operation of the vehicle. The red light, or more strictly speaking, the red lens, at one side, the usual danger color, indicates the movement of the machine,

when it is operated to take the position of the white lens, and likewise the green lens is utilized. It will, therefore, be understood that the lens carrying member 10 is 5 rotatable so as to present a proper signal and for causing rotation I employ a horizontal shaft 14 for each lens carrying member suitably supported by brackets 15 on the dashboard 2 and having a gear 16 meshing 10 with the gear 10. At the opposite end of the shaft 14 a second gear 17 meshes with a horizontal gear 18 carried by the upper extremity of the vertical operating shaft 19. Projecting rearwardly from the shaft 19 15 is an operating lever 20 which has at its rearmost extremity a pivoted section 21 adapted to be operated by means of the foot. The pivoted section 21 is held in slightly raised position by a strong leaf spring 22 and 20 said section engages with a retarding member somewhat in the nature of a brake 23. The purpose of this last-mentioned element is to obtain a proper operation or positioning of the lens members and for this purpose 25 the pivoted section 21 engages in notches 24 located at the ends and at the central point of the member 23. When in the central notch the lens carrying member is in the normal position with the white light showing forwardly, and when in the end notches the respective green and red lights are disclosed. It will be understood, of course, 30 that the operator need only press the pivoted section 21 downwardly to disengage 35 the same whereupon the lever 20 may be moved laterally to cause the rotation of the vertical shaft 19 which correspondingly rotates the horizontal shafts 14, shifting the respective lens carrying members to proper 40 position according to the direction the vehicle is to take.

For the purpose of illuminating the lights 6 of the lamps, I provide a main source of electric current, such as the battery A which 45 is of sufficient power to be utilized for constant illumination as when the vehicle is operated at night. However, for day usage, a source of electric current B of less power may be employed and this is possible by 50 reason of the fact that the signals are only operated intermittently as when it is desired to designate the contemplated movement of the vehicle, all as will be more clearly understood from a further perusal 55 of this description.

The electric source A is connected by the main supply circuit C to the spaced terminals 25, 26, in the switch box D, said box contains a rotatable switch member 27 carrying spaced arms 28 and spring lever 29. 60 In constant contact with the switch member 27, most clearly shown in Figs. 5 and 6, is a terminal block 30 from which circuit wires 31 lead to the side lights, said wires prefer-

ably being housed within the tubular support 7, as shown in Fig. 4 of the drawing.

The auxiliary electric source B is connected to the terminals 32, 33, by the circuit wires E, as shown in Fig. 4. However, the circuit E is normally an open circuit and 70 has interposed therein a circuit closing member 34 which is carried by the gear segment 35 intermeshing with a gear 36 on the vertical shaft 19. The circuit closing member 34 is of such shape or configuration as to 75 coat with the spaced terminals 37, 38, when the segment 35 is shifted by the shaft 19 in rotation thereof in either direction, but under normal conditions as shown in Fig. 4, the circuit closing member 34 maintains the 80 circuit from the auxiliary source B in open condition.

Now describing the use of the apparatus, it will be understood that when the vehicle is operated at night and a constant illumination of the light 6 is desired, the lever 29 of the switch box D is moved upwardly to the contact marked N, being held upon this contact button in the usual manner by reason of the spring action of the lever 29. 85 The current is, therefore, maintained and when it is desired to indicate the direction of movement toward the right, as will be indicated by a red light, the operator shifts the lever 20 toward the right bringing the 90 red lens of the right lamp to the forward position of the lamp. Obviously, movement in the other direction of the vehicle may be indicated by shifting of the lever in the reverse direction to that just mentioned. A 95 particular feature of this device may here be mentioned, having reference to the construction of the casing projection 4, of each lamp which is cut away at its outer and under portion as indicated at 4', and at the 100 front extremity or rim of the projection and at the cut away portion just mentioned is disposed a mirror 4'' which is designed primarily to reflect the signal in a rearward direction so that the traffic at the rear may 105 also be apprised of the movement of the vehicle. The mirror or reflector is doubly serviceable in that it illuminates the running board quite adequately to enable occupants of the machine to see clearly when getting in or out of the same.

During use of the vehicle in the daytime, the switch lever 29 is shifted downwardly to the terminal marked D whereupon the projections 28 will connect with the terminals 120 32, 33, where before they connected with the terminals 25, 26 for the main night source A. No signal in this position is given obviously because of the circuit E being broken until the vehicle is to move either to the 125 right or to the left, whereupon the operator shifts the lever 20 causing the circuit closing member 34 to contact with the terminals 37,

38. flashing a green and a red signal in the proper lamps according to the direction to be taken. The drain upon the source B is, therefore, only intermittent and such source 5 need not be as strong as that indicated at A. It is immaterial whether ordinary batteries or other generator devices are used in carrying out this function.

Having thus described my invention, what 10 I claim as new is:

1. In a signal device of the class described, the combination with an illuminant signal, of means for operating said signal, means for illuminating the signal, and means for 15 rendering the illuminating means constant, or effective only under control of the operating means aforesaid.

2. In a device of the class described, the combination with a multicolored signal, operating means for presenting a predetermined signal color including a shifting member, means for illuminating said signal, including an electric circuit, and means for illuminating certain of said signal colors 25 only, under control of the shifting member comprising a control member movable in one direction to establish a constant illumination and in the other direction to afford a temporary illumination.

30. 3. In combination, a casing, a lens carrying member, means for imparting rotation to said lens carrying member, a light associated with the lens carrying member, an electric circuit for said light, a switch in 35 said circuit for maintaining illumination of said light, said switch being operable to interrupt the circuit to transfer control of said circuit to the rotating means aforesaid.

4. In combination, a casing, a lens carrying member, means for imparting rotation to said lens carrying member, a light associated with the lens carrying member, an electric circuit for said light, a switch in 45 said circuit for maintaining illumination of said light, said switch being operable to interrupt the circuit for control by the rotating means aforesaid, and circuit closing means adapted to close the circuit on operation of the rotating means.

50. 5. In combination, a casing, a lens carrying member, means for rotating said lens carrying member, a light associated with the lens carrying member, an electric circuit for said light, a circuit closing means in said 55 circuit for automatically closing the circuit when the lens carrying member is moved by the rotating means aforesaid for flashing a

signal, and breaking said circuit upon restoration of said lens carrying member to normal position, and separate means for 60 maintaining the circuit closed and the light operative independent of said circuit closing means.

6. In combination, a signal, a light for illuminating said signal, operating means 65 for said signal, main and auxiliary sources of current for said light, independent circuits therefor, and means for rendering the main source of current effective for constant illumination, or the auxiliary source effective 70 for intermittent illumination under control of the operating means aforesaid.

7. In combination, a signal, a light for illuminating said signal, operating means 75 for said signal, main and auxiliary sources of current for said light, independent circuits therefor, means for rendering the main source of current effective for constant illumination, or the auxiliary source effective 80 for intermittent illumination under control of the operating means aforesaid, including a switch in said circuits movable in one direction to close the main circuit and in the other direction for rendering the auxiliary circuit effective, and circuit closing 85 means in the auxiliary circuit operable by the operating means aforesaid.

8. In combination, a casing, a rotatable lens carrying member disposed therewithin, a plurality of lenses carried thereon shiftable for signal purposes, a light associated with the lens carrying member, a source of electric current for said light, a switch for connecting said source with the light for night illumination, operating means for 95 moving the lenses to signal therewith, a second source of electric current for said light adapted to be connected therewith by said switch for day use, and means operable by the aforesaid operating means when the 100 switch is in position for day use to effect an illumination of the light for signaling.

9. In a device of the class described, the combination with a multi-colored signal, operating means for presenting a predetermined signal color, means for illuminating said signal, control means shiftable in one direction for rendering the illuminating means effective independent of the operating means and in the other direction for rendering said illuminating action subject 105 to the control of the operating means.

In testimony whereof I affix my signature.

WILLIAM K. PORTER.
